UNITED STATES PATENT OFFICE.

CHARLES HULTGREN, OF CHICAGO, ILLINOIS, ASSIGNOR TO S. KARPEN & BROS., OF CHICAGO, ILLINOIS, A CORPORATION OF WEST VIRGINIA.

BEDSTEAD.

1,405,219.

Specification of Letters Patent.

Patented Jan. 31, 1922.

Application filed November 20, 1920. Serial No. 425,307.

To all whom it may concern:

Be it known that I, CHARLES HULTGREN, a citizen of the United States, residing at Chicago, in the county of Cook and State of Illinois, have invented a new and useful Improvement in Bedsteads, of which the following is a specification.

This invention relates particularly to bedsteads in which the longitudinal members, 10 or side-rails, are detachably connected with the end standards.

The primary object is to provide an improved connection between the side-rails and end standards, whereby the side-rails may 15 be secured with the utmost rigidity and staunchness to the end standard, the connections nevertheless permitting the parts to be assembled and disconnected with ease and facility.

20 The invention is illustrated, in its preferred embodiment, in the accompanying drawing, in which—

Fig. 1 represents a broken perspective view of a side-rail of a bed, as constructed 25 in accordance with the invention; Fig. 2, a broken perspective view of one of the uprights or posts of an end standard; Fig. 3, a broken longitudinal sectional view, showing the side-rail connected with the post, 30 the section being taken as indicated at line 3 of Fig. 1; Fig. 4, a broken horizontal section taken as indicated at line 4 of Fig. 3; Fig. 5, a broken horizontal sectional view showing a modification in which the tightening lever employed is made to swing in 35 a horizontal plane instead of a vertical plane; and Fig. 6, a broken vertical sectional view showing one of the posts of a wooden end standard, adapted for use in 40 connection with the invention.

Referring to Figs. 1 to 4, inclusive, A represents one of the posts of an end standard of a bed; B, one of the longitudinal side-members or side-rails of the bed; B', a bearing member which forms a slidable extension 45 for the rail B; and C, means for shifting the members B and B' with relation to each other to effect a tightening or clamping action of the bearing member B' against the 50 corner-post of the bed.

The post A is shown as a tubular metal post provided interiorly, at the point of connection with the rail, with a reinforcing sleeve 1. Through the tubular post and

the reinforcing member 1 is cut a T-slot 2, 55 which has the enlarged upper portion 2^a and the reduced lower portion 2^b.

The rail B is shown as an angle-form metal rail which is provided at its extremity with a transverse flange 3. This flange 60 has a tapped hole therein through which is screwed a screw-bolt 4, which is equipped with a lock-nut 5. The rounded head 4^a of the screw-bolt is adapted to be passed through the enlarged portion 2^a of the slot 2, 65 and the head of the bolt will engage the reduced portion 2^b of the T-slot when the rail is in the position with reference to the post which is shown in Fig. 3. Thus, interlocking connection between the post A and 70 the rail B is provided. The rail B has its vertical flange equipped with an inwardly projecting lateral stud 6, which is adapted to serve as a cam-stud.

The bearing-member B' is of U-form 75 cross-section, being provided with a top member 7 and side-members 7^a and 7^b. The side-members may be of approximately triangular or truncated triangular form, as shown. The member B' is further provided 80 with a concave end wall which is adapted to engage the rounded surface of the corner post. This wall may be formed by extending the side flanges 7^a and 7^b and bending them into a transverse plane and then concaving them, thus forming the members 7^c and 7^d, respectively. The whole member B' may be thus conveniently formed of strong sheet metal. The shank of the screw-bolt 4 extends freely through a perforation in the 85 members 7^c and 7^d. The member B' embraces the end portion of the rail B and is adapted to slide thereon, the shank of the screw-bolt 4 at the same time sliding through the perforation in the members 7^c 90 and 7^d.

The tightening device C comprises a cam-lever having a head-portion 8 and a handle portion 8^a. The head-portion 8 is journaled on a transverse stud 9 which has its ends 100 secured to the side-members 7^a and 7^b of the bearing member B'. The vertical flange of the rail B is provided with a longitudinal slot 10 through which the rivet or stud 9 extends. The lever C has its head portion 105 8 provided with an eccentric or cam surface 8^b which is presented upwardly and towards the cam-stud 6.

When the slidable bearing member B' and the rail B are in collapsed relation, the stud or screw-bolt 4 may be entered readily through the T-slot 2, after which the lever C 5 may be swung to the position shown in Fig. 3, thus forcing the member B' against the post A and forcing the rail B in the opposite direction, so that the wall of the post is firmly clamped between the head of the 10 screw-bolt and the concave bearing surface of the member B' . When the handle 8^a of the lever is in the elevated position shown in Fig. 3, the cam-stud 6 rests in a slight recess 8^c at the base or extremity of the cam surface 8^b , and the lever will remain, by reason of the frictional engagement, in the locked position shown in Figure 3. When it is desired to separate the rail from the end standard, it is necessary only to throw the 15 handle 8^a of the cam-lever C downwardly, thus relieving the tension, after which the rail may be removed by lifting it and then withdrawing it.

In the modification shown in Fig. 5, B^2 25 represents a longitudinal rail; B^3 represents a slidable bearing member similar to the bearing member B' ; and C' represents a cam-lever adapted to swing in a horizontal plane. In this case, the cam-stud carried by the rail B is designated 6^a ; and the side-members 7^a and 7^b of the slidable bearing member B^3 have connected therewith a cross-member 11 which is provided with a 30 horizontal slot in which is mounted the head portion of the lever C' , the head portion being connected with the cross-member 11 by a pivot 11^a . The cam-lever is provided with a suitable cam 12 for coacting with the cam-stud 6^a . The parts are shown in locked 35 position in Fig. 5. If the handle of the cam-lever be swung away from the vertical flange of the rail B^2 , the parts will be released.

Fig. 6 shows a wooden corner-post A' 45 equipped with a socket-plate 13 which is provided with a T-slot 14. It is obvious that the socket-plate 13 may receive the head of a stud, such as the screw-bolt 4, and the invention may thus be employed in 50 connection with a bedstead having a wooden end standard. Obviously, the shape of the end wall of the slidable bearing member B' may be suitable for a rounded post or for a post having a flat surface, as desired.

55 The improved construction is adapted to provide exceedingly tight and staunch connections between the rails and end standards of a bedstead. Nevertheless, the parts may be readily assembled or disassembled.

60 The foregoing detailed description has been given for clearness of understanding only and no unnecessary limitations should be understood therefrom, but the appended claims should be construed as broadly as 65 permissible in view of the prior art.

What I regard as new, and desire to secure by Letters Patent, is—

1. The combination with a bedstead post and a longitudinal rail, of a stud adapted to connect said parts, and a lever device 70 mounted on the rail and adapted to force said parts apart and tighten the connection.

2. The combination of an end standard of a bed provided with a slot, a side-rail having a headed stud projecting from the end 75 thereof and engaging said slot, and a cam device adapted to force said side-rail away from the end standard and tighten the connection.

3. The combination of an end standard 80 of a bed provided with a slot, a side-rail equipped with a headed stud engaging said slot, a slidable bearing member engaging the standard and forming an extension of the side-rail, and means for forcing said bearing member against said standard and said side-rail in the opposite direction to tighten the connection.

4. The combination of an end standard of a bed, a side-rail, a connecting member connecting said parts, a bearing member 90 slidable with relation to the side-rail and engaging said end standard, and a lever adapted to force said bearing member against the end standard and said side-rail 95 in the opposite direction to tighten the connection.

5. The combination of an end standard of a bed, a side-rail, a slidable bearing member 100 housing the end portion of said side-rail and engaging the end standard, a connection between the extremity of the said rail and the end standard, and means for shifting said side-rail and said bearing member with relation to each other, to tighten the connection, said means including a lever at the inner side of said side-rail.

6. The combination of an end standard, a side-rail, a stud carried by said side-rail and adapted to detachably engage the end standard, a bearing member engaging the end standard and housing the end portion of the rail, and a cam device adapted to shift said side-rail with relation to said bearing member to tighten the connection.

7. The combination of an end standard, a side-rail, a stud carried by said side-rail and adapted to detachably engage the end standard, a bearing member engaging the end standard and housing the end portion of the rail, a cam device for shifting said rail with relation to said bearing member comprising a cam stud carried by one of said parts, and a cam-lever carried by the other of said parts and adapted to coat 120 with said cam-stud.

8. The combination of an end standard provided with a slot, a side-rail equipped with a headed stud adapted to engage said slot, a bearing member engaging said stand- 130

ard and slidably related to said side-rail, a stud carried by said bearing member, a cam-lever mounted on said stud, and a cam-stud carried by said side-rail and adapted to be 5 engaged by said cam-lever.

9. The combination of an end standard provided with a slot, an angle-form side-rail equipped at its extremity with a headed stud adapted to engage said slot, a bearing 10 member housing the end portion of said rail and adapted to engage said standard, a cam-stud carried by the vertical flange of said rail, a pivot stud carried by the side flanges of said bearing member and disposed between 15 said cam-stud and the end of the rail, and a cam-lever mounted on said pivot stud and having a cam portion interposed between the pivot-stud and the cam-stud and having a handle portion sheathed by said 20 side-rail when in locked position.

10. In means of the character set forth, the combination of a post equipped with a T-slot, an angle-form side-rail having an end wall equipped with a headed stud 25 adapted to engage said T-slot, a bearing member sheathing the end portion of said side-rail and engaging said post, and cam means carried by the side-rail and bearing

member and adapted to shift said parts with relation to each other to effect tightening 30 of the connection.

11. In means of the character set forth, the combination of a post provided with a T slot, a side-rail, a headed stud adjustably connected with said side-rail and adapted 35 to engage said slot, a bearing member interposed between the side-rail and said post, and cam means carried by said side-rail and bearing member and adapted to shift the side-rail with relation to the bearing mem- 40 ber to effect tightening of the connection.

12. In means of the character set forth, the combination of a post provided with a T slot, a side-rail equipped with a headed longitudinal stud adapted to engage said 45 slot, a bearing member slidably connected with the side-rail and having an end wall engaging said post, said end wall being provided with a passage for the shank of said stud, and a cam device mounted on said side-rail and bearing member and adapted to shift the side-rail with relation to the bearing member to effect tightening of the connection. 50

CHARLES HULTGREN.
